UNITED STATES PATENT OFFICE.

SAMUEL K. DAVIES, OF NEWPORT, KENTUCKY, ASSIGNOR TO LEE E. ACH, OF CINCINNATI, OHIO.

HAT-SHAPING MACHINE.

1,201,266.

Specification of Letters Patent. Patented Oct. 17, 1916.

Application filed September 15, 1915. Serial No. 50,768.

To all whom it may concern:

Be it known that I, SAMUEL K. DAVIES, a citizen of the United States, residing at Newport, in the county of Campbell and State of Kentucky, have invented certain new and useful Improvements in Hat-Shaping Machines, of which the following is a specification.

It is the object of my invention to provide a new and improved machine for shaping hats, especially bulged portions of hats.

Machines of this character as heretofore usually employed comprised a pair of solid molds one received about the other, the material to be shaped being pressed between the molds, each of the molds being heated and the material being dampened before application of the molds thereto, the material remaining between the solid molds until substantially dry and set to shape. In practice under employment of these means, pressure was applied throughout a substantial portion of the surface of the material, and the molds, when being set, also exerted sliding pressure or ironing upon the surface of the material, whereby the nap of the material, for instance velvet, was crushed, and operations were subsequently necessary to attempt to restore the nap, which, in practice was expensive and very often impossible owing to the pressure and heat previously applied to the material; furthermore a large waste of material resulted from the necessity of having material in sufficiently large pieces to permit the stretching of the material by hand over the lower mold, so that the solid upper mold could be received thereabout while the material was being held in stretched relation by the manual stretching.

It is the object of my invention to avoid the objections stated, and to provide means whereby the upper or outer mold may be dispensed with, and the cost of forming the same and the metal of the mold consequently saved; further to provide a mold about which the material is arranged to be stretched; further to provide a flexible tension-member to be received about the mold for maintaining the material in stretched relation and fixing the material to the shape of the mold; and, further to provide means whereby the shaping and drying of the material is accelerated.

It is the object of my invention further to provide a flexible tension-member movable

with relation to the mold for arranging the flexible tension-member in co-operative position with relation to the mold about the material to be shaped, and to stretch the same about said material; further to provide adjusting means whereby the location of the tension-member about the mold may be adjusted, and, further, to insure ready release of said material by the tension-member; further to mount the tension-member upon a movable frame movable toward and from the position of the mold, and to provide means for stretching the tension-member in operative position; further to so relate the positioning and stretching means as to insure release of the stretching means from the material prior to moving the tension means from the mold, and the invention will be further readily understood from the following description and claims, and from the drawings, in which latter:

Figure 1 represents a front elevation of my improved device. Fig. 2 is a side elevation of the same. Fig. 3 is a vertical cross-section taken on the line 3—3 of Fig. 1. Fig. 4 is a plan view of my improved device. Fig. 5 is a horizontal cross-section taken on the line 5—5 of Fig. 2. Fig. 6 is a horizontal cross-section of the same taken on the line 6—6 of Fig. 2. Fig. 7 is a horizontal cross-section of the same taken on the line 7—7 of Fig. 2. Fig. 8 is a detail view in cross-section on the line 8—8 of Fig. 1. Fig. 9 is a detail view in vertical cross-section taken on the line 3—3 of Fig. 1, showing the positioning lever in down position and the pulling lever in up position. Fig. 10 is a side elevation showing a detail of the left side of the positioning lever. Fig. 11 is a detail view of one of the arms for the flexible tension-member, partly in section on the line 11—11 of Fig. 5. Fig. 12 is a detail view in section on the line 12—12 of Fig. 1; and Fig. 13 is a detail view in section on the line 13—13 of Fig. 12.

21 represents the main frame of the machine, with relation to which a slide-frame 22 is movable. The slide-frame, in the present exemplification, comprises upright rods 23 connected at their upper ends by a cross-piece 24 and at their lower ends by a cross-girt 25, the rods sliding in bearings 26 in the main frame. The cross-piece 24 was arranged in machines as heretofore employed to have an upper solid mold, coact-

ing with the lower mold herein shown, suspended therefrom by suitable clamps in slots 27.

A head 30, shown in the form of a plate or spider, is located at the top portion of the sliding frame and is adjustable thereon by means of the nuts 31, 32, adjustable lengthwise of the threaded ends 33 of the rods 23, for adjusting the head lengthwise of said rods and clamping said head in adjusted positions, the upper cross-piece 24, in the present exemplification, being adjustable with the head.

The main frame is provided with a table 35 having a socket 36 in which the stem 37 of a pedestal 38 is secured, a lower mold 39 being clamped to the pedestal by means of the hook-clamps 40. The mold may be of any desired shape or size, depending on the shape or size it is desired to give the crown or bulged portion of the hat or hat-part to be shaped. By means of my improved device the material is arranged to be shaped upon the mold for forming a bulging portion of the hat or hat-part, and intricate contours may be shaped. I have shown the mold about which the shaping is to be accomplished as having a crown whose lower end is curved and extends different distances lengthwise of the axis of the hat-crown at different portions about the periphery of the crown. The same mold may, however, be used in my improved device for shaping crowns whose sides are of equal height throughout the periphery of the crown and to shape crowns of various heights upon the mold merely by adjusting the position of the tension-member or the directions in which it extends.

For accomplishing my purpose I employ a flexible tension-member, shown at 46, received about the mold at a point corresponding to the bottom of the crown or bulged portion to be formed. This tension-member may be instanced as being a wire-cable, and is arranged to be placed in position about the mold, and when in such position to be drawn taut about the mold at the location representing the bottom of the crown or bulged part for firmly holding the material in stretched relation about the mold. The mold is arranged to be heated, as by gas through the medium of gas-jets supplied from suitable openings in a ring-pipe 47 fed by a pipe 48 leading to a suitable point and provided with a valve 49.

In the present exemplification, the tension-member is arranged to be supported in position to be received about the mold by rods 51, which are normally held in such position that the tension-member when received about the mold is distanced from the mold, being preferably spring-pressed laterally to a position away from said mold, accomplished, in the present instance by form-

ing said rods of spring material, so as to constitute said rods spring-rods. The tension-member is shown supported by the rods by means of clips 52 secured to the free ends of the rods, as by means of screws 53, the clips 52 having a spring-tongue 54 under which the tension-member is received. The clip is of thin material and quite narrow, so as to afford as smooth a surface as possible throughout the path of the tension-member about the mold. The closed path of the tension-member is exemplified at 55, from which the stretches 56 thereof extend in opposite directions toward the sides of the machine, the tension-member at the inner ends of said stretches crossing each other in the clip, as indicated in Fig. 3. The tension-member is drawn taut about the mold by suitable means, exemplified as extensions of said tension-member, although other means may be employed. It is to be understood that the term, flexible tension-member, wherever employed does not include such drawing or pulling means. The extensions of the tension-member are exemplified as stretches 56 continued over pulleys 57 as stretches 58 which are continued over pulleys 59 as stretches 60 which are continued over pulleys 61 as stretches 62 received about a pulley 63 acting as an equalizer pulley and arranged to be pulled for applying tension to the tension-member.

The head 30 is provided with slots 71 shown as radiating slots, in which the rods 51 are adjustable lengthwise of said slot, the rods being also adjustable crosswise of the plate, or axially, as by having threaded portions 72 over which nuts 73, 74, are received for determining the normal positions of said rods lengthwise thereof with relation to the mold and for clamping the rods in the slots in adjusted positions to conform to the shape of the mold. The rods are thus positioned or adjusted to conform to the diameters of the shape of the mold and heights of the various portions of the sides of the mold, or at equal elevations, depending on the shape of the crown or hat-part to be formed, but so arranged as to be normally spaced from the wall of the mold when the tension-member is in position about the mold for being pulled taut for shaping the material.

In my improved device, motion is imparted between the tension-member and the mold so as to cause the tension-member to surround the mold, accomplished in the present exemplification by depressing the tension-member.

The material to be stretched may be any desired fabric, for instance, buckram, velvet, or any other fabric to form a hat-part having a bulge therein. The material is dampened prior to being shaped. A usual material employed is buckramette, which

has been provided with a stiffening and gluing substance and dampened and having a piece of velvet undampened laid thereon, the two superposed materials being placed 5 about the crown of the mold and then pulled downwardly over the mold by the operators, two operators usually serving the machine, and both operators taking the superposed materials by means of their hands and pulling 10 the same over the mold. By means of my improved device the material may be so cut as to leave only sufficient material in the piece being shaped as to afford a grip thereon by the hands of the operators beyond 15 the line at which the tension-member is to be stretched about the material, represented in the present exemplification as the line 75. The space occupied by the tension-member which would interfere with the hands of the operators, is comparatively 20 small and the waste of material is therefore very slight.

In the usual devices now employed for pressing the hat material to shape, the solid 25 mold received about the mold represented at 39 is necessarily of thick metal so as to retain the heat, and in practice extended to the line 76, so that the operators in stretching the material necessarily had to hold 30 the material at points beyond said line 76, necessitating the use of larger pieces of material, it being necessary after the shaping was accomplished to cut away all the material beyond the line 75, making the old 35 methods extremely wasteful of material, which is saved by my improved device. By employment of said usual devices, furthermore, the mold received about the mold 39 approached the mold 39 in a line parallel to 40 the axis of the mold, causing a seating of the mold upon the material with a movement substantially parallel to the line of the side of the crown, causing a sliding of the heated upper solid mold upon said side 45 of the material with an ironing motion, whereby the nap of the material was crushed and destroyed, the restoration of this nap being very expensive and very often impossible, which objections are avoided 50 by my improved device, in which the tension-member is first moved toward the mold 39 in a line parallel to the axis of said mold, but distanced from said mold, the pulling of said tension-member taut about the mold 55 being accomplished after said tension-member has been seated in lateral position, so that the nap of the material is retained, except at the narrow line of contact of the tension-member with the material, which in 60 practice is adjacent to the seam-line of the hat and is unexposed in the finished hat.

Means employed for depressing the sliding frame are exemplified as a treadle 81 pivoted on a tie-rod 82 between the side- 65 frames 83, 84, of the main frame.

85, 86, are a pair of pendant rods, supported at their lower ends from the side-frame by means of a fork-piece 87. Notches 88, acting as keepers, are located at the lower ends of the pendant rods for receiving 70 the treadle 81 when the latter is depressed for holding the same in depressed position, thereby depressing the flexible tension-member and locating the same about the mold 39. A link 90 is pivoted about 75 a pin 91 articulated with the treadle 81 and has a bearing 92 about an eccentric 93 on a rock-shaft 94 journaled in bearings 95, 96, in the slide-frame, and having an operating arm 97 secured thereto. An additional depression may be given the slide-frame by the forward movement of the arm 97, if such is desired.

For normally causing raising movement of the slide-frame, I provide a rocker-frame 85 101 pivoted in bearings 102 in the side-frames of the main frame and provided with arms 103. Links 104 are articulated with said arms at 105 and with lugs 106 of the slide-frame. A rod 107 is mounted in bearings 108 in the arms 103 and in a bearing 109 in an arm 110, integral with the rocker-frame. Counterbalance springs 111 extend between the rod 107 and the table 35, the tension of the springs being adjusted by 95 bolts 112 extending through the table and held thereto by the heads of the bolts and threaded in blocks 113 about which the upper ends of the springs are coiled.

Means are provided for adjusting the positions of the operating parts receiving the stretches extending directly from the flexible tension-member, according to the adjustments of said flexible tension-member, so that said stretches may be located in substantially the plane of said tension-member, accomplished by adjusting the positions of the axes about which said stretches move, exemplified as the axes of rotation of the pulleys 57, shown as shoulder-bolts 121 received through the pulleys and through pulley-housings 122, the bolts passing through slots 123 in slides 124 and clamp-nuts 125, whereby the pulley-housings and pulleys 59 are located in adjusted positions. 100 Each of the slides 124 has a slide-member 126 adjustable in a guide 127 and arranged to be clamped in adjusted positions by means of bolts 128 passing through apertures in said guide and through a slot 129 in said slide, and threaded into a clamp-plate 130 clamped against the inner face of said slide. The guides are shown as extending rearwardly, the rear ends of said guides being connected and held in spaced-apart relations 105 by means of a tie-rod 133 passing through bearings 134 in said guides, nuts 135, 136, at the respective sides of said bearings clamping said bearings and tie-rods together. A 110 combined structure is thus formed for the 120 125 130 135 140 145 150 155 160 165 170 175 180

positioning of the bolts 121, adjustable lengthwise of the sliding frame by means of clamp-bearings 137 clamped in adjusted positions by means of bolts 138 about the rods 23. The lower directing members for the operating means for the flexible tension-member, exemplified as the pulleys 59, 61, also have their pivotal axes arranged to move with the slide-frame, for accomplishing which the pivotal axes are shown as shoulder-bolts 140 passing through said pulleys and the housings 141, 142, thereabout, being threaded into a tie-rod 143 fixed in bearings 144 of hangers 145 extending forwardly from the upright rods 23 and clamped to the latter by means of clamp-bearings 146 clamped by clamp-bolts 147.

The pulley 63, exemplified as an equalizer pulley, has the stretches 62 passing thereabout and is pivoted in a housing 151. A lever 152, exemplified as a treadle, is provided for exerting pull upon the flexible tension-member. It is pivoted by a bearing 153 about the articulating pin 91. It is exemplified as connected with the housing 151 by means of a wire cable 154 between which and the housing 151 a spring 155 is interposed. The cable is wound about a drum 156 mounted on the treadle 152, being journaled on a pin 157 in a bearing 158 in said treadle and a bearing 159 in a bracket 160 extending from the treadle, the drum being provided with a flange 161 provided with holes 162 for receiving a spanner-wrench for winding the drum and with a ratchet-wheel 163 with which a ratchet-tooth 164 coacts, the ratchet-tooth being pivoted on a pin 165 fixed in the treadle 152 by means of a set-bolt 166.

In operation, after the material has been manually stretched about the mold, as hereinbefore described, the treadle 81 is depressed for depressing the flexible tension-member, thereby positioning the flexible tension-member laterally with relation to the mold. The tension-member is then pulled by operation of the treadle 152 about the material held in stretched relation about the mold for maintaining the material in such stretched relation, and the treadle 152 is then held in depressed position for the period of time which may be necessary to dry the material, and thereby fix the same into the shape determined by the mold and tension-member. The mold is a heated mold and the tension-member contacts only a line of space around the material, leaving the balance of the material open to the atmosphere, so that the steam and vapor resulting from the drying action of the heated mold upon the material, is readily diffused away from the material, whereby the time of drying of the material is materially shortened. When the material is dry, the tension-member is released. It is desirable

that the release of the tension-member shall be insured in such manner as to avoid a movement of the tension-member along the face of the material while contacting the material. I accomplish this by providing retaining means for the treadle 152 which shall be released by actuation of the treadle 81, so as to insure a release of the tension-member and spreading of the rods 51 prior to the raising of the tension-member with relation to the mold. Thus the pin 165 is extended so as to coact with a keeper 171 on the treadle 81. The keeper is mounted on an arm 172 pivoted on a bolt 173 in a housing 174, clamped to the lever 81 by means of a strap 175 and bolts 176. The keeper is held in normal coacting position with relation to the pin 165 by means of a spring 181 extending between the housing 174 and the arm 172. An auxiliary treadle 182 is pivoted to the housing 174 on a pin 183 and a lug 184 thereon is adapted to engage the heel 185 of the arm 172 for moving the keeper 171 out of range with the pin 165. The operator places his foot upon the auxiliary treadle 182 extending above the treadle 81 and thereby depresses the treadle 81 for depressing the flexible tension-member and slide-frame and the parts mounted thereon, bringing the treadle 81 into the keeper 88 for positioning said treadle in depressed position. The depression of the treadle 81 depresses the pivotal point of the lever 152. The elevation of the lever 152 with relation to the lever 81 is determined by the winding or unwinding of the drum 156. The operator then depresses the treadle 152, the pin 165 thereon striking the latch face 186 of the keeper 171 and being received under the keeper 171, the spring 181 causing the movement of said keeper over the pin. After sufficient time has elapsed for drying the material upon the form, the operator places his foot on the auxiliary treadle 182, thereby releasing the keeper 171 and causing the treadle 152 to rise, owing to the spread of the spring-arms 51, thereby spreading the flexible tension-member away from the material about the mold. Upon disengagement of the lever 81 from its keeper 88, the lever 81 is permitted to rise, due to the action of the counterbalance springs 111 for raising the slide-frame of the machine. The shaped material may then be removed from the mold and trimmed, little trimming, however, being necessary and waste of material being reduced to the minimum in my improved device, owing to the fact that the operator in stretching the material can grip the material close to the flexible tension-member. My improved device has the further advantage that, after the engagement of the flexible tension-member with the material, the operator may re-arrange the material under 130

the tension-member by local stretching at points thereof, so as to insure any degree of stretching that may be desired locally, or to control the shape of the stretching as may be desired, the operator having the whole of the material in full view.

My improved device is so arranged that the tension-member and its supporting and operating parts may be attached to any 10 sign of stamper hat press to which it is adapted, replacing the upper solid mold of the same, avoiding the disadvantages of said upper mold and saving the gas consumption necessary to heat the upper mold, 15 and providing a better finished article.

Having thus fully described my invention, what I claim as new and desire to secure by Letters Patent, is:

1. In a hat shaping machine, the combination with a mold, of a flexible tension-member arranged to be received about said mold, means for causing movement between said tension-member and mold axially of said mold during operation of the machine for causing said tension-member to be received about said mold or to be distanced therefrom, and means for drawing said tension member taut about said mold.

2. In a hat shaping machine, the combination with a mold, of a flexible tension-member, means for causing movement between said tension-member and said mold axially of said mold during operation of the machine for causing positioning of said tension-member in or out of the lateral projection of said mold, and means for causing said tension member to be drawn taut about said mold.

3. In a hat shaping machine, the combination with a mold, of a flexible tension-member, means for adjusting the normal relation between said tension-member and said mold, means for causing movement between said tension-member and said mold axially of said mold during operation of the machine to bring said tension-member and said mold within range and out of range of one another, and means for drawing said tension-member taut about said mold.

4. In a hat shaping machine, the combination with a mold, of a flexible tension-member, means for adjusting the normal relation between said tension-member and said mold, means for causing movement between said tension-member and said mold axially of said mold during operation of the machine to bring said tension-member and said mold within range and out of range of one another, means for normally separating said tension-member laterally from said mold, and means for drawing said tension-member taut about said mold.

5. In a hat shaping machine, the combination with a mold, of a flexible tension-member, means for adjusting the normal relation

between said tension-member and said mold, means for causing movement between said tension-member and said mold axially of said mold during operation of the machine to bring said tension-member and said mold within range and out of range of one another, means for positioning said tension-member in laterally separated relation from and about said mold, means for adjusting the normal positions of said last-named means laterally with relation to said mold, and means for drawing said tension-member taut about said mold.

6. In a hat shaping machine, the combination with a mold, of a flexible tension-member, means for resiliently supporting said tension-member with relation to said mold, means comprising a treadle for causing movement between said tension-member and said mold to bring said tension-member and said mold within range and out of range of one another, a latch for said treadle, means comprising a treadle for drawing said tension-member taut about said mold, and a latch for said last-named treadle, said last-named treadle having operative connection with said first-named treadle.

7. In a hat shaping machine, the combination with a mold, of a flexible tension-member, means for resiliently supporting said tension-member with relation to said mold, means comprising a treadle for causing movement between said tension-member and said mold to bring said tension-member and said mold within range and out of range of one another, a latch for said treadle, means comprising a treadle for drawing said tension-member taut about said mold, and a latch for said last-named treadle, said first-named treadle comprising a releasing member for said last-named latch.

8. In a hat shaping machine, the combination of a main frame, a slide-frame thereon, said main frame arranged for supporting a mold, a supporting part on said slide-frame, rods supported thereby, a flexible tension-member supported by said rods, operating means for said tension-member comprising directing parts mounted on said slide-frame, said tension-member being normally separated in the direction of movement of said slide-frame from said mold, means for simultaneously moving said slide-frame, tension-member and directing parts for positioning said tension-member about said mold separated in lateral directions from said mold, and means for drawing said tension-member taut about said mold.

9. In a hat shaping machine, the combination with a mold, of a flexible tension-member, rods extending toward said mold, said rods provided with holding means for said flexible tension-member, means for adjusting the normal positions of said holding means with relation to one another and to

- said mold for adjusting the normal directions in which said flexible tension-member extends, and means for drawing said flexible tension-member taut about said mold.
- 5 10. In a hat shaping machine, the combination with a mold, of a flexible tension-member, spring-rods extending toward said mold, said rods provided with holding means for said flexible tension-member,
- 10 means for adjusting the normal positions of said rods with relation to one another and to said mold for adjusting the normal directions in which said flexible tension-member extends, means for causing movement between said holding means and said mold for locating said tension-member within and outside of the lateral projection of said mold, and means for drawing said tension-member taut about said mold.
- 15 11. In a hat shaping machine, the combination with a mold, of a movable frame comprising a head, rods adjustably mounted on said head, a flexible tension-member supported by said rods, means for moving said movable frame toward and from said mold, means for adjusting said head on said movable frame for collectively adjusting said rods, and means for drawing said flexible tension-member taut about said mold.
- 20 12. In a hat shaping machine, the combination of a main frame comprising a table adapted to support a mold, a slide-frame mounted on said main frame, a flexible tension-member adjustably supported on said slide-frame, means for moving said slide-frame for locating said tension-member within and out of range of a mold supported by said table, and means for drawing said flexible tension-member taut about said mold
- 25 comprising operating stretches extending laterally above said table from said flexible tension-member toward the sides of said slide-frame, downwardly past the sides of said table and laterally under said table and
- 30 movable with said slide-frame.
- 35 13. In a hat shaping machine, the combination with a main frame comprising a mold-support, a slide-frame slidable on said main frame, means for sliding said slide-frame with its upper end movable toward and from said mold-support, and means for maintaining said slide-frame in down-position, of a head removably secured to said
- 40 slide-frame, a flexible tension-member supported thereby, and means for drawing said tension-member taut about the mold on said mold-support comprising supporting parts removably secured to said slide-frame.
- 45 14. In a hat shaping machine, the combination with a mold-support, of a flexible tension-member arranged to be received about a mold on said mold-support, means for adjusting the normal position of said flexible tension-member comprising a head, rods adjustable laterally and axially thereon, supporting means on said rods for said flexible tension-member, and means for drawing said tension-member taut.
- 50 15. In a hat shaping machine, the combination with a mold-support, of a flexible tension-member arranged to be received about a mold on said mold-support, means for adjusting the normal position of said flexible tension-member comprising a head, rods adjustable laterally and axially thereon, supporting means on said rods for said flexible tension-member, and means for drawing said tension-member taut, said last-named means comprising a pair of directing parts located respectively at the sides of said collective rods, and means for adjusting said pair of parts up and down and forwardly and rearwardly with relation to said rods.
- 55 16. In a hat shaping machine, the combination with a main frame and a mold-support therein, of a slide-frame slidable on said main frame, a head thereon, rods adjustable laterally and axially thereon, a flexible tension-member supported by said rods, and means for drawing said tension-member taut comprising a pair of directing members located above said table respectively at the sides of said collective rods, means for adjusting the latter up and down and forwardly and rearwardly with relation to said rods, and directing parts under said table, said directing parts being mounted on and movable with said slide-frame.
- 60 In testimony whereof, I have hereunto signed my name in the presence of two subscribing witnesses.
